(57) **CLAIM**

The ornamental design for an implant removal tool and assembly, as shown and described.

DESCRIPTION

FIG. 1 is a perspective view of the implant removal tool and assembly;

FIG. 2 is a front view of the design for the implant removal tool and assembly of FIG. 1;

FIG. 3 is a back view of the design for the implant removal tool and assembly of FIG. 1;

FIG. 4 is a first side view of the design for the implant removal tool and assembly of FIG. 1;

FIG. 5 is a second side view of the design for the implant removal tool and assembly of FIG. 1;

FIG. 6 is a top view for the design for the implant removal tool and assembly of FIG. 1;

FIG. 7 is a bottom view for the design of the implant removal tool and assembly of FIG. 1; and,

FIG. 8 is a perspective exploded view for the design of the implant removal tool and assembly of FIG. 1.

The broken line showing in the drawings is included for the purpose of illustrating portions of the implant removal tool and assembly and forms no part of the claimed design.
